UNITED STATES PATENT OFFICE.

WILLARD D. LOWE, OF COLUMBUS, OHIO.

SCRIBING CALIPERS.

Application filed February 2, 1921, Serial No. 441,757. Renewed January 5, 1923.

To all whom it may concern:

Be it known that WILLARD D. LOWE, a citizen of the United States, residing at Columbus, in the county of Franklin and 5 State of Ohio, has invented certain new and useful Improvements in Scribing Calipers, of which the following is a specification.

This invention relates to an improved scribing caliper, primarily adapted for use 10 by machinists and other metal workers for the purpose of enabling fine and careful measurements to be effected with convenience, accuracy and facility and to enable the calipers to be readily adapted for the purpose 15 of producing guide lines or the like upon desired surfaces from ruling edges situated inside or outside of the arms of the calipers.

Another object of the invention resides in 20 the provision of an instrument of the above character which consists of a pair of arms having adjoining ends pivotally connected in order that the lower ends thereof may be relatively separated for suitable distances, 25 in providing the arms with means whereby the lower ends of the arms will normally be separated and to have their relatively spaced positions maintained by means of screw controlled mechanism, to form one of said arms 30 with a scribe point, and to provide the other arm with a pivotally mounted guide foot, the latter being so arranged that it may be swung to assume one of a plurality of positions, the arrangement thereof being such 35 that when the foot is in one position the same will be adapted to cooperate with a ruling element or surface situated within the confines of the arms, and when situated in its other position to cooperate with a 40 ruling or guide surface positioned exteriorly of the arms, the arrangement making for convenience in operation and to enable the instrument to be under the convenient and facile control of the operator.

45 With these and other objects in view, as will appear as the description proceeds, the invention accordingly consists in the novel features of construction, combinations of elements and arrangements of parts, herein- 50 after to be fully described and pointed out in the appended claims.

In the accompanying drawing forming a part of this specification, and in which similar characters of reference denote like and 55 corresponding parts throughout the several views thereof:

Figure 1 is a perspective view of a pair of calipers constructed in accordance with the principles of the invention.

Figure 2 is a detail view disclosing the 60 calipers in a position for outside work,

Figure 3 is a similar view disclosing the calipers in position for inside work,

Figure 4 is a detail view of the guide foot, and 65

Figure 5 is a transverse sectional view taken along the line 5—5 of Figure 1.

Referring more particularly to the details of the invention, use is made of a pair of calipers 1 primarily adapted for measuring 70 and scribing purposes, the same in this instance including a pair of pivotally connected arms, one of said arms being termed the scribing arm and indicated generally by the numeral 2, and the other or companion 75 arm being termed the guide arm, and indicated generally by the numeral 3. These arms have their upper ends pivotally connected by means of the joint construction 4, and the extreme upper ends of the said arms 80 are formed with projections 5, having notches therein for the reception of the free ends of a spring 6, the latter being so disposed that by the contraction of its ends the lower ends of the arms 2 and 3 will normally 85 tend to separate or spread apart. To regulate the distance between the lower ends of the arms 2 and 3, the arm 2 is provided with a pivoted apertured stud 7, which is adapted to receive one end of an adjusting screw 8, 90 the said screw being so disposed as to extend transversely of the arms and has its outer or free end pass through an aperture provided in a pivoted stud 9 projecting from the guide arm 3. The free end of the screw 95 is provided with an adjusting nut 10, which may be moved into binding engagement with the stud 9 for the purpose of permitting of the contracting or expanding of the arms 2 and 3 in accordance with the normal tension of the spring 6. 100

In order to render such instruments more readily adapted for various kinds of work, the lower end of the guide arm 3 is relatively bluntly terminated and is provided 105 with a pivot pin 11 about which is pivotally mounted an adjustable crescent shaped guide foot 12. This member is pivoted intermediate of its length and by its formation guide fingers 13 and 14 are produced. These 110 fingers are capable of occupying active or inactive positions in accordance with the

relative positions which the calipers may assume with respect to a ruling edge, indicated generally by the numeral 15. For instance, as shown in Figure 2, if the finger 14 assumes its active position, the calipers may be used with the guide arm 3 outside of the confines of the ruling edge 15 and, conversely, in the event that the finger 13 is swung to assume an active position, as indicated in Figure 3, the calipers may be used to inscribe a mark with the arm 3 within the confines of the ruling edge 15. By this pivoted arrangement, therefore, of the foot 12 it is possible for a machinist to readily adapt the calipers to the work to be performed, and the awkwardness of the average caliper of common construction is lost. In the old forms, the foot 12 is ordinarily fixed or integrally formed with the guide arm and therefore the calipers are capable of being readily employed when the ruling edge 15 is properly situated with respect to the surface to be scored, but difficulty will be encountered in these old forms if the work to be secured is located on a side of the ruling edge upon which the stationary foot can not be readily placed. However, by the reversible foot construction of the calipers 1 this difficulty is largely obviated and convenience in the handling of the instrument obtained. Also, by the screw construction 8 the instrument may be carefully, accurately yet expeditiously adjusted, and adjustments maintained, thus overcoming the difficulty involved in instruments where adjustments are maintained by mere frictional pressure between the arms.

If desired the fingers 13 and 14 may be provided with burrs 16, which are capable of resiliently engaging with depressions 17 provided in the guide arm 3, in order that the said foot 12 may be maintained in any of its adjusted positions, or in certain constructions the burrs 16 may be omitted and the friction pressure between the foot and the guide arm relied upon for the purpose of maintaining adjustments of the foot 12.

What is claimed is:

1. A pair of scribing calipers comprising a pair of arms having their upper ends pivotally connected, one of said arms being provided with a pointed scribing extremity, the

other of said arms having its companion end relatively bluntly terminated, and the reversible foot pivotally connected to the blunt end of said arm and capable of assuming positions of adjustment admitting said guide foot to be adapted to contact with either the inner or outer surface of a ruling member.

2. A pair of calipers comprising a scribing arm and a guide arm, a pivotal connection between the ends of said arms, spring means cooperative with said pivotal connection and normally tending to separate the free ends of said arms, an adjustment for regulating the distance between the free ends of said arms, the free end of the scribing arm being provided with a pointed extremity, and the free end of said guide arm being provided with a reversible guide foot capable of adapting the instrument to contact with inside and outside ruling surfaces.

3. A pair of scribing calipers comprising a guide arm and a scribing arm, means for pivotally uniting the upper ends of said arms and to maintain the free ends of said arms in set positions of adjustment, said scribing arm being formed to include a substantially pointed free extremity, and said guide arm being formed to include a substantially blunt lower or free extremity, and a substantially crescent shaped guide foot pivotally connected with said guide arm extremity and capable of assuming positions adapting the instrument to contact with exterior and interior ruling surfaces.

4. A pair of calipers comprising a scribing arm and a guiding arm, means for pivotally connecting the upper ends of said arms and to maintain the arms in relatively set positions of adjustment, a substantially crescent shaped guide foot pivotally carried by the lower end of the scribing arm, said guide foot including relatively spaced fingers, the latter being selectively capable of assuming active or inactive positions, whereby the instrument may be adapted to contact with both exterior and interior ruling surfaces, and means for positively maintaining said guide foot in its fixed positions of adjustment.

In testimony whereof I affix my signature.

WILLARD D. LOWE.
